JEWELRY DISPLAY CASE

Howard Ferguson, Valley Cottage, N.Y., assignor to Bulova Watch Company, Inc., New York, N.Y.

Filed Oct. 30, 1972, Ser. No. 302,471

Term of patent 7 years

Int. Cl. D6—04

U.S. Cl. D6—25

FIG. 1 is a front and right side perspective view of a jewelry display case showing my new design with the cover in open position;

FIG. 2 is a right side elevational view with the cover in closed position;

FIG. 3 is a right side elevational view with the cover in open position; and

FIG. 4 is a rear elevational view with the cover in closed position.

I claim:

The ornamental design for a jewelry display case, substantially as shown and described.
